UNITED STATES PATENT OFFICE.

EDWARD POOLE, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,800, dated April 16, 1872.

Specification describing a new and original Design for a Carpet, invented by EDWARD POOLE, of Halifax, in the county of York, England.

The accompanying photograph fully illustrates my new design.

This invention relates to a new design in which there are two main figures—one a large square, with a V-shaped notch or depression in the middle of each side, and the other a narrow rectangle—both having ornamental borders and central decoration, as shown.

I claim as my invention—

The design for a carpet, containing the figures as shown and described.

EDWARD POOLE.
